UNITED STATES PATENT OFFICE.

LOUIS C. TIFFANY, OF NEW YORK, N. Y.

DESIGN FOR A LAMP-SHADE.

45,205.

Specification for Design.

Patented Feb. 3, 1914.

Application filed July 24, 1913. Serial No. 781,030. Term of patent 8½ years.

To all whom it may concern:

Be it known that I, LOUIS C. TIFFANY, a citizen of the United States, residing in the city of New York, borough of Manhattan, in the county and State of New York, have invented a new, original, and ornamental Design for a Lamp-Shade, of which the following is a specification, reference being had to the accompanying drawing, forming part thereof.

I claim:

The ornamental design for a lamp shade, as shown.

LOUIS C. TIFFANY.
